PRODUCTION OF POLYALKYL BENZENES

William G. Toland, Jr., San Rafael, and L. G. Williams, Richmond, Calif., assignors to California Research Corporation, San Francisco, Calif., a corporation of Delaware

No Drawing. Application June 17, 1954

Serial No. 437,587

6 Claims. (Cl. 260—668)

This invention relates to a process for the production of polyalkyl benzene hydrocarbons. More particularly, it relates to an improved method for producing polymethyl benzene hydrocarbons in a manner adapted to yield a particular polymethyl benzene isomer of high purity.

Pursuant to the invention, polyalkyl benzenes having at least 3 alkyl groups substituted on the nucleus are prepared by a process which comprises reacting an aromatic hydrocarbon feed having a substantial content of dialkyl benzene hydrocarbons with formaldehyde to form a di-arylmethane hydrocarbon product, subjecting the di-arylmethane to hydrogenolysis to produce alkyl benzene hydrocarbons and fractionally distilling the hydrogenolysis product to recover a polyalkyl benzene hydrocarbon having at least 3 alkyl groups substituted on the nucleus.

The process of the invention can be adapted to produce a variety of useful results. If any xylene isomer or a mixture of xylene isomers is condensed with formaldehyde to produce a di-xylyl methane and the dixylyl methane is then reacted with hydrogen under hydrogenolysis conditions, the di-xylyl methane molecule is split, producing one molecule of xylene and one molecule of trimethyl benzene. The trimethyl benzene product is found to consist of about 90% or more by volume of pseudocumene, irrespective of which xylene isomer is used as the starting material. The process of the invention thus provides a means for obtaining pseudocumene in high purity without recourse to involved methods for separating the isomeric trimethyl benzenes.

It is found, pursuant to the invention, that metaxylylene condenses with formaldehyde to form a dixylyl methane much more rapidly than do ortho-xylene or para-xylene. It is thus possible to employ the process of the invention to manufacture pseudocumene and simultaneously produce a para-xylene of high purity by charging a xylene feed which consists predominantly of metaxylylene and para-xylene to the process and limiting the amount of formaldehyde charged to the process to a quantity stoichiometrically insufficient to condense all of the xylenes fed to the process to di-arylmethanes, but sufficient to condense the major proportion of the metaxylylene fed to the process to di-arylmethane.

The process of the invention may also be employed to produce pseudocumene and a xylene product predominating in para-xylene by charging a mixture of xylenes and toluene to the process. The condensation product produced by reaction of this feed with formaldehyde will contain di-xylyl methane, xylyl tolyl methane and ditolyl methane. Hydrogenolysis of this reaction product will produce a mixture of pseudocumene, xylene and toluene.

The process of the invention can also be employed to manufacture durene by condensation of xylenes with formaldehyde and hydrogenolysis of the product to produce high purity pseudocumene, which is then condensed with formaldehyde to form a di-pseudocumyl methane which, on hydrogenolysis, yields durene. By proceeding further, for example, by condensing durene with formaldehyde and hydrogenolysis, penta-methyl and hexamethyl benzenes can be produced.

It is possible to produce pseudocumene or higher polymethyl benzenes pursuant to the process by using either

2

benzene or toluene as a starting material. If benzene is employed, the first hydrogenolysis product consists of benzene and toluene. When this product is condensed with formaldehyde and subjected to hydrogenolysis, the resulting second hydrogenolysis product contains xylene, toluene and benzene. A further condensation and hydrogenolysis yields a product containing benzene, toluene, xylene and pseudocumene. A still further condensation of this product followed by hydrogenolysis yields a product containing benzene, toluene, xylene, pseudocumene and durene, etc.

The reactions occurring in the process of the invention are illustrated by the following equations which show the production of pseudocumene and durene:

The process of the invention is illustrated by the following examples:

EXAMPLE 1

The relative rates of reaction of the xylene isomers were established by condensing each isomer individually with formaldehyde under similar conditions and following the rate of disappearance of formaldehyde by periodical sampling of the aqueous phase for analysis. The reaction was run in a glass turbomixer, to which the xylene was added, and heated to 200° F.-220° F. A mixture of sulfuric acid and formaldehyde was passed into the turbomixer during a period of 35 minutes and then the resulting mixture was digested for a further period of 3 hours. The results obtained in these runs are set forth in the following table:

Table

Charge Stock	Para-xylene, 95.3%	Ortho-xylene, 97%	Meta-xylene, 96.3%
Run No.	2548-26	2588-15	2588-21
Xylene, mols C ₆	5.71	5.80	5.66
Formalin, mols H ₂ CO	1.02	1.01	1.01
50 Wt. percent H ₂ SO ₄ , mols H ₂ SO ₄	1.81	1.84	1.82
H ₂ CO Conversion (Mol percent):			
after 0.5 hr. digestion	48.0	65.3	97.8
after 2.0 hr. digestion	70.6	80.2	-----
after 2.5 hr. digestion	80.8	83.8	-----
after 3.0 hr. digestion	86.6	-----	-----

Those runs made to isolate the trimethylbenzenes produced made use of the azeotroping technique of removing water of reaction from the condensation step as formed, permitting the use of less sulfuric acid than is necessary otherwise. The condensation products were washed free of acid and distilled to recover unconverted xylene, dixylylmethane, and polymer. The dixylylmethane was then passed over molybdena-alumina catalyst containing 8-12% molybdena with hydrogen and the products were distilled to obtain a xylene fraction, a C₉ aromatics cut, and unconverted dixylylmethane.

EXAMPLE 2

A 1.5-liter turbomixer, equipped with an inlet tube at the base, heating coil, thermowell, and reflux condenser with a water separator, was charged with 613.8 g. (700 cc.) (5.78 mols) of 97.0% ortho-xylene and 296.0 g. (190 cc.) (2.05 mols) of 67.5 weight percent sulfuric acid. The mixture was heated with stirring to reflux, giving a liquid-phase temperature of 263° F.-270° F. Aqueous formaldehyde solution (37% formalin) was then introduced through the inlet tube at the rate of 1 cc. per minute until a total of 82.2 g. (76 cc.) (1.01 mols) had been added. During this time, the reflux was controlled to remove water from the separator at essentially this same rate in order to maintain a constant concentration of acid in the reactor. A total of 71.0 g. (73 cc.) of water phase was collected and was found to contain 0.09 g. of formaldehyde.

The reaction products, weighing 912.3 g., were removed and cooled, permitting a separation of two liquid phases; an organic phase of 617.5 g. (680 cc.) and an aqueous phase of 293 g. (190 cc.), which was found to contain 66.8% sulfuric acid by weight. The acid layer was separated and the organic phase washed with dilute caustic and water before distilling through a one-foot

helices packed column to recover 389.9 g. (451 cc.) (3.67 mols) of ortho-xylene, 189.1 g. (194 cc.) (0.845 mol) of diortho-xylylmethane boiling at 218° C.-222° C. at 50 mm. of mercury, and 21.8 g. of higher polymer bottoms.

The conversion of formaldehyde was 99.7% and of ortho-xylene was 36.5%, to give an 80.2% yield of theory of dixylylmethanes from ortho-xylene and an 84.0% yield of theory from formaldehyde.

A total of 146 g. (150 cc.) of the diortho-xylylmethane was fed at a rate of 1 cc. per minute to the catalyst chamber with hydrogen fed at 6.0 cu. ft. per hour. The chamber consisted of a 30-inch vertical stainless steel pipe of $\frac{3}{4}$ -inch I. D. fitted with a $\frac{3}{4}$ -inch O. D. thermowell and heated by a mercury bath under nitrogen pressure to 750° F. The catalyst, 49 g. (53 cc.) of pellets of molybdenum oxide (12% by weight) on alumina formed a bed 13 inches deep. Liquid products, condensed in an ice trap followed by a "Dry Ice" cooled trap, consisted of 142.3 g. (156 cc.). Distillation through a three-foot helices packed column yielded 32.8 g. (37.8 cc.) of ortho-xylene, boiling point 142° C.-147° C.; an intermediate cut of 10 g., boiling point 147° C.-163° C.; a trimethylbenzene cut, boiling point 163° C.-169° C., of 36.8 g.; and still bottoms of recovered feed, 55.2 g.

Infrared analysis of the trimethylbenzene fraction showed:

	Volume percent
Ortho-xylene	3.5
1,2,4-trimethylbenzene	93.0
1,2,3-trimethylbenzene	3.5
1,3,5-trimethylbenzene	0.1
Total	100.0

Of the C₉ aromatics, the 1,2,4-trimethylbenzene (pseudocumene) is 96.3%.

This shows a 62.2% conversion of diortho-xylylmethane with a 70.8 mol percent yield of 1,2,4-trimethylbenzene.

EXAMPLE 3

The same procedure and equipment was made as for ortho-xylene, using the following materials in the indicated quantities: 608 g. (700 cc.) (5.75 mols) of 96.3% meta-xylene, 301.2 g. (190 cc.) (2.07 mols) of 67.5 weight percent sulfuric acid, and 82.8 g. (77 cc.) (1.02 mols) of 37% formalin. A total of 73.0 g. (77 cc.) of water was removed during reaction by azeotroping and contained 0.006 g. formaldehyde. The reaction products, 912 g., yielded 615.1 g. (685 cc.) of organic layer and 296.0 g. (190 cc.) of aqueous acid phase of 65.8% sulfuric acid by weight. After distillation, there was obtained 368.0 g. (427 cc.) (3.47 mols) of meta-xylene, 188.9 g. (195 cc.) (0.844 mol) of dimeta-xylylmethane boiling at 211° C.-215° C. at 50 mm. of mercury, and 18.6 g. of higher polymer bottoms.

The conversion of formaldehyde was 99.9% and of meta-xylene was 39.7%, to give a yield of dimeta-xylylmethane of 74.2% of theory from meta-xylene and of 83.0% of theory from formaldehyde.

Following the same procedure used in Example 2, 144 g. (150 cc.) of dimeta-xylylmethane was fed with hydrogen over the catalyst bed. Liquid products, 142.7 g. (158 cc.) on fractional distillation, gave 42.1 g. of meta-xylene, boiling point 138° C.-145° C.; 6.0 g. of an intermediate fraction, boiling point 145° C.-163° C.; 43.7 g. of a trimethylbenzene fraction; and 45.1 g. of unconverted feed.

Infrared analysis of the trimethylbenzene fraction showed:

	Volume percent
Meta-xylene	2.3
1,2,4-trimethylbenzene	93.0
1,2,3-trimethylbenzene	4.0
1,3,5-trimethylbenzene	0.7
Total	100.0

Of the C₉ aromatics, the 1,2,4-trimethylbenzene (pseudocumene) is 95.2%.

This shows a 68.8% conversion of dimeta-xylylmethane with a 76.6 mol percent yield of pseudocumene in a single pass.

EXAMPLE 4

Again using the same equipment and procedure as for ortho-xylene, in Example 2, the following materials in the indicated quantities were employed: 602.8 g. (700 cc.) (5.68 mols) of 95.2% para-xylene, 302.5 g. (192 cc.) (2.06 mols) of 68 weight percent sulfuric acid, and 82.7 g. (77 cc.) (1.02 mols) of 37% formalin. A total of 73.8 g. (74.8 cc.) of water was removed by azeotroping and was found to contain 0.03 g. of formaldehyde. The reaction products, 897.3 g., yielded 538.7 g. (608 cc.) of organic layer and 349.1 g. of an acid emulsion. Caustic treating resulted in a 162.5 g. loss in weight of the organic layer, from which some para-xylene was later recovered by stripping. An additional increment was recovered similarly from the acid emulsion. Distillation of the organic phase yielded 237.9 g. of para-xylene, 121.7 g. of dipara-xylylmethane, a white crystalline solid at room temperature which boiled at 202° C.-207° C. at 50 mm. of mercury, and 15.4 g. higher polymer bottoms.

The conversion of formaldehyde was 99.9% and of para-xylene was 41.7%, to give a yield of dipara-xylylmethane of 70.8% of theory from para-xylene and of 81.6% of theory from formaldehyde, including the products recoverable from the emulsions.

Because dipara-xylylmethane is a solid at room temperature, it was dissolved in benzene to give a 50 weight percent solution, which was introduced at 4 cc. per minute with 6 cu. ft. per hour of hydrogen through the same equipment and catalyst bed as before, at 750° F., until a total of 1003 g. (1093 cc.) of solution, containing 501.5 g. of dipara-xylylmethane, had been fed. A total of 992.5 g. of liquid products was recovered, which on distillation gave 502.5 g. of benzene; 9.8 g. of intermediate boiling to 137° C.; a para-xylene fraction of 45.4 g., boiling point 137° C.-140° C.; and intermediate fraction, boiling from 141° C. to 166° C. of 23.6 g.; a trimethylbenzene fraction of 43.5 g., boiling point 166° C.-169.5° C.; and recovered dipara-xylylmethane, 362.5 g.

Infrared analysis of the trimethylbenzene fraction showed:

	Volume percent
Xylenes	1.5
1,2,4-trimethylbenzene	97.5
1,2,3-trimethylbenzene	0.5
1,3,5-trimethylbenzene	0.3
Total	99.8

Of the C₉ aromatics, the 1,2,4-trimethylbenzene (pseudocumene) is 99.2%.

This shows a 27.6% conversion of dipara-xylylmethane with a 57.0 mol percent yield of isolated pseudocumene in a single pass over the catalyst.

EXAMPLE 5

Using the same equipment and procedure as in Example 2, the following materials in the indicated quantities were charged: 395.9 g. (460 cc.) (3.99 mols) of mixed xylenetoluene blend of the following composition (infrared analysis):

	Volume percent
Ethylbenzene	1.2
Ortho-xylene	16.8
Meta-xylene	17.7
Para-xylene	17.2
Toluene	45.6
Total	98.5

plus 91.9 g. (60 cc.) (0.645 mol) of 68.7 weight percent sulfuric acid, and 81.5 g. (76 cc.) (1.02 mols) of 37% formaldehyde solution (formalin). A total of 76.4 g. (78 cc.) of water was removed by azeotroping and was found to contain 0.92 g. of formaldehyde. The reaction products, 505.0 g., yielded 392.2 g. (430 cc.) of organic layer and 110.1 g. (79 cc.) of an acid emulsion layer. After caustic treating and distillation there was obtained 27.9 g. of higher polymer material, 145.3 g. (146 cc.) of di-arylmethanes boiling at 194° C.-216° C. at 50 mm. of mercury, and 193.7 g. (224 cc.) of unconverted organic feed stock of the following composition by infrared analysis methods:

	Volume percent
Ethylbenzene	0
Ortho-xylene	18.5
Meta-xylene	5.7
Para-xylene	22.4
Toluene	52.8
Total	99.4

The conversion of the formaldehyde was 97.3% and of the aromatics was 44.8 mol percent to give a yield of di-arylmethanes of 85.3% of theory from the aromatics and 77.0% of theory from formaldehyde. The conversions of the individual organic compounds were 100% for the ethylbenzene, 60% for ortho-xylene, 83% for meta-xylene, 30% for para-xylene and 37% for toluene.

Following the same procedure used in Example 2, 141.7 g. (145 cc.) (0.665 mol) of the di-arylmethanes was fed with hydrogen over the catalyst bed. Liquid products, 138.6 g. (151 cc.) on fractional distillation gave 47.7 g. (56 cc.) of a toluene-xylene fraction boiling at 111° C.-160° C.; a trimethylbenzene fraction, boiling range 160° C.-170° C., of 16.2 g. (18.5 cc.); and a still bottoms of recovered di-arylmethanes, 66.0 g.

Infrared analysis of the toluene-xylene fraction showed:

	Volume percent
Ethylbenzene	1.5
Toluene	13.5
Ortho-xylene	15.5
Meta-xylene	34.1
Para-xylene	28.9
1,2,4-trimethylbenzene	2.5
Total	96.0

Infrared analysis of the trimethylbenzene fraction showed:

	Volume percent
Ortho-xylene	5.0
1,2,4-trimethylbenzene	85.0
1,3,5-trimethylbenzene	0.5
1,2,3-trimethylbenzene	8.0
Total	98.5

This run showed a 53.5% conversion of di-arylmethanes per single converter pass operation.

Adjusting all analysis data to 100 volume percent totals, and then normalizing for organic handling losses in the condensation and hydrogenolysis steps, the net absolute conversions and yields for the two-step process (based upon a 100% hydrogenolysis conversion of the di-arylmethane feed stock) may be tabulated as follows:

	(A)		(B)		(A→B)	
	Condensation Conversions		Hydrogenolysis Yields		Net Con- ver- sion	Net Yield
	g.	moles	g.	moles		
Ethylbenzene	4.7	0.044	1.9	0.018	0.026	-----
Ortho-xylene	27.4	0.258	21.8	0.206	0.052	-----
Meta-xylene	59.0	0.557	43.4	0.410	0.147	-----
Para-xylene	20.4	0.192	36.8	0.347	-----	0.155
Toluene	67.9	0.738	17.3	0.188	0.830	-----
1,2,4-trimethylbenzene			39.0	0.325	-----	0.325
1,2,3-trimethylbenzene			3.4	0.028	-----	0.028
1,3,5-trimethylbenzene			0.2	0.002	-----	0.002
Totals	179.4	1.789	163.8	1.524	0.775	0.510
(-CH ₂ -) from HCHO	13.9	0.99				
Di-arylmethane yield	162.3	1.524/N ₁				
Polymer yield	31.0	0.265/N ₂				

(N₁=2).
(N₂>3).

EXAMPLE 6

Using the same equipment and procedure as in Example 2, the following materials in the indicated quantities were charged: 434.8 g. (501 cc.) (3.84 moles) aromatic feed stock of the following composition as analyzed by infrared methods:

	Volume percent
Meta-xylene	1
Ortho-xylene	48
1,3,5-trimethylbenzene	0.5
1,2,4-trimethylbenzene	1.48
1,2,3-trimethylbenzene	2
Total	99.5

¹ Pseudocumene.

plus 112.1 g. (72 cc.) (0.77 mol) of 67.5 weight percent sulfuric acid, and 81.0 g. (76 cc.) (1.0 mol) of 37% formaldehyde solution (formalin). A total of 73.8 g. (75 cc.) of water was removed by azeotroping and was found to contain 0.10 g. of formaldehyde. The reaction products, 574.1 g., yielded 435.5 g. (475 cc.) of organic layer and 107.4 g. (70 cc.) of 65.9 weight percent sulfuric acid. After caustic treating and distillation, there was obtained 206.8 g. (268 cc.) (1.87 moles) of aromatic feed stock of the following composition:

	Volume percent
Ortho-xylene	62.0
1,2,4-trimethylbenzene	37.0
1,2,3-trimethylbenzene	1.0
Total	100.0

plus 198.1 g. (200 cc.) of co-condensation products boiling at 220° C.-240° C. at 50 mm. of mercury, and 26.2 g. of higher polymer bottoms.

The conversion of formaldehyde was 99.7% of ortho-xylene was 38.6% and of pseudocumene was 63.2% to give a di-arylmethane yield of 82.8% based on aromatics converted.

Following the same procedure used in Example 2, 180.5 g. (190 cc.) of the di-arylmethanes was fed with hydrogen over the catalyst bed. Liquid products, 176.8 g. (199 cc.) on fractional distillation gave 140.6 g. (160 cc.) of hydrogenolysis products, boiling range 160° C.-214° C. at 760 mm. of mercury, and 33.5 g. (34 cc.) of unconverted di-arylmethanes, boiling range 218-242° C. at 50 mm. of mercury.

Infrared analysis of the hydrogenolysis product fraction showed:

	Volume percent
Ortho-xylene	8
1,3,5-trimethylbenzene	1
1,2,4-trimethylbenzene	61
1,2,3-trimethylbenzene	5
30 1,2,4,5-tetramethylbenzene	23
1,2,3,5-tetramethylbenzene	2

Total 100

Normalizing for organic handling losses in the condensation and hydrogenolysis steps, and comparing overall absolute conversions and yields for the two-step process, it may be seen that this particular reaction was a breeder reaction. The amount of pseudocumene converted to durene was replaced by the ortho-xylene converted to pseudocumene. The net consumption of ortho-xylene was 0.60 mol and the net production of durene was 0.36 mol.

EXAMPLE 7

Using the same equipment and procedure as in Example 2, the following chemicals in the indicated quantities were charged: 272.0 g. (312 cc.) (2.57 moles) of toluene-pseudocumene blend of the following composition:

	Volume percent
Toluene	44.2
Ortho-xylene	1.6
1,3,5-trimethylbenzene	0.1
1,2,4-trimethylbenzene	49.6
1,2,3-trimethylbenzene	4.5

Total 100.0

plus 1140 g. (740 cc.) (7.48 moles) of 64.2 weight percent sulfuric acid, and 49 g. (45 cc.) (0.604 mol) of formalin (37% formaldehyde). A total of 46.7 g. (47 cc.) of water was removed by azeotroping and was found to contain 0.049 g. of formaldehyde. The reaction products yielded 268.7 g. of organic layer and 1075.6 g. of final acid layer. (The balance of the sulfuric acid was removed as reaction mix samples during the course of the formalin addition). After caustic treating and distribution, there was obtained 5.2 g. of higher polymer material, 124.8 g. (crystalline slurry at 20° C.) of di-arylmethanes boiling at 189° C.-235° C. at 50 mm. of mercury, and two distillation fractions of unconverted organic feed stock. The toluene fraction, boiling range 110° C.-111° C., of 77.0 g. (92 cc.) was found by analysis to have the following composition:

plus 1140 g. (740 cc.) (7.48 moles) of 64.2 weight percent sulfuric acid, and 49 g. (45 cc.) (0.604 mol) of formalin (37% formaldehyde). A total of 46.7 g. (47 cc.) of water was removed by azeotroping and was found to contain 0.049 g. of formaldehyde. The reaction products yielded 268.7 g. of organic layer and 1075.6 g. of final acid layer. (The balance of the sulfuric acid was removed as reaction mix samples during the course of the formalin addition). After caustic treating and distribution, there was obtained 5.2 g. of higher polymer material, 124.8 g. (crystalline slurry at 20° C.) of di-arylmethanes boiling at 189° C.-235° C. at 50 mm. of mercury, and two distillation fractions of unconverted organic feed stock. The toluene fraction, boiling range 110° C.-111° C., of 77.0 g. (92 cc.) was found by analysis to have the following composition:

	Volume percent
Toluene	97.6
Ortho-xylene	1.9
1,2,4-trimethylbenzene	0.5
Total	100.0

The second distillation fraction, boiling range 116° C.-170° C. at 760 mm. of mercury, of 44.3 g. (54 cc.) was found by analysis to have the following composition:

	Volume percent
Toluene	12.0
Ortho-xylene	4.0
1,3,5-trimethylbenzene	0.2
1,2,4-trimethylbenzene	79.8
1,2,3-trimethylbenzene	4.0
Total	100.0

The conversion of formaldehyde was 99.8% and of the aromatic feed stock was 52.7 mol percent to give an actual yield of di-arylmethanes of 78.6 weight percent based on the weight of aromatic feed stock and formaldehyde converted. The yield of di-arylmethanes can be increased by contacting the caustic treat emulsion layer with fresh or recycle organic feed en route to the condensation step. Normalizing for this additional possible recovery, the total aromatic conversion is 47.1 mol percent and the weight percent yield of di-arylmethanes is 96%. On this normalized basis, the individual aromatic conversions are 25 mol percent toluene, 19 mol percent ortho-xylene, 71 mol percent 1,2,4-trimethylbenzene and 84 mol percent 1,2,3-trimethylbenzene.

Following the same procedure used in Example 2, 101.8 g. (107.5 cc. liquid volume at 80° C.) of the di-arylmethanes was fed with hydrogen over the catalyst bed. Liquid products, 98.7 g., on fractional distillation gave 9.8 g. (12 cc.) of a toluene-xylene fraction boiling at 121° C.-145° C.; a trimethylbenzene fraction, boiling range 146° C.-184° C., of 41.4 g. (48.0 cc.); a tetramethylbenzene fraction, boiling range 194° C.-215° C. at 760 mm. of mercury, of 26.1 g.; and a still bottoms of recovered di-arylmethanes, 17.7 g. (liquid at 20° C.).

The composition of the toluene-xylene fraction was:

	Volume percent
Ethylbenzene	1.0
Toluene	28.5
Ortho-xylene	15.3
Meta-xylene	3.5
Para-xylene	50.7
1,2,4-trimethylbenzene	1.0
Total	100.0

The composition of the trimethylbenzene fraction was:

	Volume percent
Ortho-xylene	3
Para-xylene	2
Meta-xylene	1
1,3,5-trimethylbenzene	2
1,2,4-trimethylbenzene	79
1,2,3-trimethylbenzene	10
1,2,4,5-tetramethylbenzene	3
Total	100

The composition of the tetramethylbenzene fraction was:

	Volume percent
1,2,4-trimethylbenzene	8
1,2,4,5-tetramethylbenzene	85
1,2,3,5-tetramethylbenzene	7
Total	100

The di-arylmethane conversion for this single pass hydrogenolysis was 82.5 weight percent. Normalizing for organic handling losses in the two-step process, and balancing absolute conversions against calculated absolute yields from an extrapolated 100% di-arylmethane conversion in the hydrogenolysis step, an overall two-step process yield of 119 mol percent durene from pseudocumene and only 56 mol percent xylenes from toluene was calculated. The recovered feed stock from the single pass hydrogenolysis was a homogeneous liquid phase at 20° C., and contained very little or none of the di-pseudocumal methane, as evidenced by the lack of crystallinity, even upon seeding the recovered feed with the original condensation product crystals. For this reason and the fact that recycle hydrogenolysis of this recovered feed yielded additional toluene, xylenes, pseudocumene and durene, it is clear that the recycle feed stock was composed mainly of the ditolylmethanes and tolyl-pseudocumal methanes.

EXAMPLE 8

Using the same equipment and procedure as in Example 2, the following materials in the indicated quantities were charged: 600 g. (700 cc.) (5.66 mols) of mixed xylenes of the following composition:

	Volume percent
Para-xylene	65.8
Meta-xylene	4.2
Ortho-xylene	24.4
Total	94.4

plus 117.6 g. (75 cc.) (0.825 mol) of 68.7 weight percent sulfuric acid, and 71.9 g. (67 cc.) (0.887 mol) of 37% formaldehyde solution (formalin). A total of 59.0 g. (60 cc.) of water was removed by azeotroping and was found to contain 0.09 g. of formaldehyde. The reaction products, 721.6 g., yielded 599.6 g. (675 cc.) of organic layer and 119.3 g. (80 cc.) of 66.5 weight percent sulfuric acid. After caustic treating and distillation, there was obtained 400.4 g. (466 cc.) (3.775 mols) of unconverted xylenes of the following composition:

	Volume percent
Para-xylene	74.8
Meta-xylene	0.9
Ortho-xylene	20.2
Ethylbenzene	0.5
Total	96.4

plus 164.5 g. (168 cc.) (0.768 mol) of the di-xylylmethanes boiling at 204° C.-216° C. at 50 mm. of mercury, and 20.5 g. of higher polymer bottoms.

The conversion of formaldehyde was 99.7% and of the xylenes was 33.5%, to give a yield of di-xylylmethanes of 81.5% of theory from the xylenes and 86.8% of theory from formaldehyde. The conversions of the individual xylene isomers were 25% for the para-xylene, 86% for the meta-xylene and 45% for the ortho-xylene. The condensation resulted in a net upgrading of the para-xylene/meta-xylene ratio from 94/6 to 99/1, which allows the remaining ortho-xylene to be removed by distillation to yield a high purity (95%+) para-xylene fraction.

Following the same procedure used in Example 2, 143.6 g. (150 cc.) (0.64 mol) of the di-xylylmethanes were fed with hydrogen over the catalyst bed. Liquid products, 140.8 g. (154 cc.) on fractional distillation gave 44.3 g. (51.3 cc.) of xylene fraction, boiling range 137° C.-160° C.; a trimethylbenzene fraction, boiling range 163° C.-170° C., of 43.6 g. (50.4 cc.); and still bottoms of recovered feed, 45.9 g.

Infrared analysis of the xylene fraction showed:

	Volume percent
Ethylbenzene	1.0
Ortho-xylene	23.1
Meta-xylene	20.1
Para-xylene	56.1
1,2,4-trimethylbenzene	2.7
Total	103.0

Infrared analysis of the trimethylbenzene fraction showed:

	Volume percent
Ortho-xylene	4
1,2,4-trimethylbenzene	90
1,3,5-trimethylbenzene	1
1,2,3-trimethylbenzene	5
Total	100

This shows a 68.3% conversion of the di-xylylmethanes with a 77.0 mol percent yield of 1,2,4-trimethylbenzene.

In runs similar to those shown in the examples, it was determined that other lower alkyl benzenes behave in substantially the same manner as the methyl benzenes in the process of the invention. Thus, the alkyl substituents on the alkyl benzene hydrocarbon charged to the condensation step may be either methyl, ethyl, propyl, or butyl groups. It is desirable that the alkyl carbon bonded to the benzene nucleus be either primary or secondary, since a tendency of tertiary alkyl groups to dealkylate during hydrogenolysis has been observed. This tendency is not so marked as to make the employment of tertiary alkyl benzene hydrocarbons inoperative, but it occurs to a sufficient extent to cause significant losses in yield.

In the condensation step the alkyl benzene is condensed with formaldehyde in the manner illustrated in the examples. Instead of the formaldehyde as illustrated, para-formaldehyde or trioxymethylene may be employed and, though less satisfactory than formaldehyde, methylal undergoes a similar condensation.

The condensation is preferably catalyzed by sulfuric acid which may be employed at concentrations ranging from about 40% to about 100% by weight. If dilute sulfuric acid is employed, water is desirably removed during the course of the condensation by distillation in the manner illustrated in Example 2. If more concentrated sulfuric acid is employed, i. e., 90% by weight or higher, it is desirable to carry out the reaction in the presence of a diluent such as a lower aliphatic alcohol or acid, i. e., methanol, ethanol, glacial acetic acid, or the like. While sulfuric acid is preferred as the catalyst, other acid catalysts are effective, for example, phosphoric acid, trichloroacetic acid, ferric chloride, methane sulfonic acid, hydrofluoric acid, and the like.

The condensation can be accomplished at temperatures ranging from about 30° F. to 300° F. In general, lower temperatures are employed with the concentrated acid catalyst, i. e., sulfuric acid, at a concentration of 85% by weight or higher to avoid losses by sulfonation. If 50 to 70% sulfuric acid is employed, the condensation can be and desirably is carried out at temperatures ranging from 200 to 300° F.

Pursuant to the invention, the di-arylmethane condensation product produced in the first step of the process is cleaved by hydrogenolysis to produce alkyl benzenes. The term "hydrogenolysis" is recognized in the art as indicating the cleavage of a carbon to carbon bond accompanied by the addition of hydrogen. Hydrogenolysis is conventionally accomplished by contacting a feed and hydrogen with a hydrogenation catalyst under mild hydrogenating conditions. The hydrogenating conditions are sufficiently severe to cause cleavage of the carbon to carbon linkage in the di-arylmethane, but not sufficiently severe to cause ring hydrogenation.

The hydrogenolysis is desirably conducted at temper-

atures in the range from 650 to 900° F., preferably from 675 to 800° F., and at a pressure ranging from atmospheric to moderate superatmospheric pressures of the order of 250 p. s. i. g. At least one mol of hydrogen per mol of di-arylmethane is charged to the hydrogenolysis step. Preferably, however, a stoichiometric excess of hydrogen is employed ranging from about 3 mols of hydrogen to about 40 mols of hydrogen per mol of di-arylmethane. The di-arylmethane and hydrogen are contacted with the hydrogenolysis catalyst at space velocities in the range from 0.1 to 10 liquid volumes of di-arylmethane per volume of catalyst per hour, preferably in the range from 0.5 to 3 v./v./hr.

In the conversion of di-arylmethanes to alkyl benzenes by hydrogenolysis, the molybdenum oxide on alumina catalyst described in U. S. Patents Nos. 2,432,286 and 2,481,824 are especially suitable. However, the metals of groups VI-B, VII-B and VIII of the periodic table and their compounds, particularly the oxides and sulfides which are generally recognized as active hydrogenation catalysts, have also been found to effectively catalyze the hydrogenolysis of di-arylmethanes produced in Examples 1 to 8, inclusive, to alkyl benzenes. These active catalytic materials are commonly disposed on a carrier or support. In the process of the invention it is desirable that the support be a material which has relatively little catalytic cracking activity, for example, alumina or high purity silica-gel. The employment of high surface silica-alumina cracking catalysts as a support for the hydrogenation catalysts is desirably avoided because this type of support acts as an isomerization catalyst and causes position isomerization of the polyalkyl benzene products so that the advantage of a high concentration of a particular position isomer in the product is lost in good part.

We claim:

1. A process for producing lower alkyl benzenes having at least three lower alkyl groups attached to the benzene nucleus, which comprises condensing with formaldehyde a xylene isomer mixture feed in the presence of an acid catalyst to produce a diarylmethane hydrocarbon product, contacting the produced diarylmethane hydrocarbon product and hydrogen with a hydrogenation catalyst at from 650° F. to 900° F. and substantially atmospheric pressure to effect hydrogenolysis of the diarylmethane, and production of a reaction mixture comprising substituted benzene isomers having at least three lower alkyl groups substituted on the benzene nucleus, said reaction mixture being characterized by a very large predominance of one of said isomers, and recovering from said reaction mixture a fraction rich in said predominating isomer.

2. The method as defined in claim 1, wherein the aromatic hydrocarbon feed has a substantial content of pseudocumene.

3. A process for producing pseudocumene, which comprises condensing a mixture of xylene isomers with formaldehyde in the presence of an acid catalyst to produce a di-arylmethane product, contacting the produced di-arylmethane product and hydrogen with a hydrogenation catalyst at a temperature in the range from about 650° F. to 900° F. and substantially atmospheric pressure to cause hydrogenolysis of the di-arylmethane producing trimethyl benzenes characterized by a very large predominance of pseudocumene, and recovering pseudocumene from the hydrogenolysis reaction product.

4. A process as in claim 3, wherein pseudocumene produced is recycled to said condensing step and contacted with said mixture of xylene isomers and formaldehyde, and wherein durene is recovered from the hydrogenolysis reaction product.

5. A process for producing durene, which comprises condensing pseudocumene with formaldehyde in the presence of an acid catalyst to produce a di-arylmethane

hydrocarbon product, contacting the produced di-aryl-methane product and hydrogen with a hydrogenation catalyst at a temperature in the range from about 650° F. to 900° F. and substantially atmospheric pressure to cause hydrogenolysis of the di-arylmethane producing tetramethyl benzenes characterized by a very large predominance of durene, and recovering durene from the hydrogenolysis reaction product.

6. A process for producing durene, which comprises condensing a mixture of pseudocumene and a methyl benzene hydrocarbon selected from the group consisting of xylenes and toluene with formaldehyde in the presence of an acid catalyst to produce a di-arylmethane hydrocarbon product, contacting the produced di-arylmethane product and hydrogen with a hydrogenation catalyst at a temperature in the range from about 650° F. to 900° F. and substantially atmospheric pressure to cause hydrogenolysis of the di-arylmethane producing tetramethyl benzenes characterized by a very large predominance of durene, and recovering durene from the hydrogenolysis reaction product.
